UNITED STATES PATENT OFFICE.

RICHARD MERCER, OF HARROW, WILLIAM H. PAULETT, OF WANDSWORTH, LONDON,
AND FRANK TENCH, OF WEST NORWOOD, LONDON, ENGLAND, ASSIGNEES, BY
MESNE ASSIGNMENTS, TO AUTOMATIC ELECTRIC INC., OF CHICAGO, ILLINOIS, A
CORPORATION OF DELAWARE.

TELEPHONE SYSTEM.

Application filed October 4, 1924, Serial No. 741,550, and in Great Britain October 13, 1923.

The present invention concerns improvements in or relating to automatic or semi-automatic telephone systems and the main object of the invention may be stated broadly 5 to be the provision of improved circuit arrangements permitting dialling to take place over both speaking leads in series and supervision to be effected over the speaking leads independently. Under these circumstances the admitted advantages of loop dialling may be combined with those of supervision as employed in standard manual practice and by means of the invention, without any serious complication of the 10 switches and other apparatus.

According to one feature of the invention setting and supervision are effected over the same leads under different circuit conditions and the setting conditions are maintained 20 until the setting operation has been completed as far as possible i. e. either the wanted party's line has been connected with or the busy signal has been received, whereupon circuit changes take place to introduce 25 supervisory conditions.

According to another feature of the invention where operators' positions are provided with dial switches to enable the operators to set up connections over automatic switches, the normally closed off normal springs of the dial switch are adapted to close a point in the energizing circuit of the line relay of an automatic switch which in turn causes a second point 30 to be closed independently of said springs so that the line relay is connected in a loop circuit during dialling. It is further arranged that the circuit for the line relay is not completed until the operator throws 35 her dialling key so that there is no danger of false impulses being sent owing to careless plugging in.

A further feature of the invention is that a switching device is provided arranged to 40 be automatically operated after impulses have been transmitted and before a supervisory signal has been sent to replace the metallic circuit across the speaking leads used for dialling by a circuit including the 45 supervisory apparatus.

Still another feature of the invention is that the connections over which battery is fed forward to or in the direction of a called

party during conversation are maintained 55 open by a relay initially energized in a local circuit, maintained energized by battery fed back from succeeding switches over the two speaking conductors in series during the setting of said switches and deenergized 60 when the connection is extended as far as possible towards the wanted line.

The circuit of this relay is preferably 65 maintained intact while the connection is being extended through intermediate switches by the provision of make-before-break springs on the wiper relays of the various intermediate selectors.

These and other features not specifically mentioned at this point will be more fully 70 understood from the following description 70 taken in conjunction with the accompanying drawings. It will be understood however that the embodiment of the invention now to be described is given by way of example only and that considerable modifications in 75 the circuit details might be made by those skilled in the art without exceeding the scope of the invention.

Referring now to the drawings,

Fig. 1 shows a local selector embodying 80 the invention.

Fig. 2 an incoming selector,

Fig. 3 an intermediate selector, and

Fig. 4 a connector.

It is intended that these four figures should 85 be placed together with the corresponding lines in alignment in order that the connection which is about to be described may be traced out.

Fig. 5 shows the apparatus provided at a 90 complaint or inquiry operator's position, while

Figs. 6 and 7 show respectively an operator's cord circuit and selector, such as 95 would be used for extending a connection from an A operator over a trunk line and over automatic switches to a distant exchange.

In the connection between two automatic subscribers it will be considered that only 100 one digit is used for exchange selection, this digit operating the local selector which then seizes a trunk line leading to the incoming selector from which the connection is then 105 extended over an intermediate selector to a connector. It will be realized that with

such a train of switches the number dialled by the subscriber will comprise 5 digits and that the system therefore might consist of 10 exchanges each of 10,000 lines capacity. 5 It will be realized however that the invention is in no way limited to a system of this size, and that additional switches of one or other of the various types described may be added as necessary and conversely 10 one or more of the switching stages may be omitted.

Considering now the setting up of a connection, it will be assumed that the first selector shown in Fig. 1 is accessible over 15 the usual subscriber's line switch, which, being well known in the art, is not shown. When the line switch seizes the selector shown and switches through, a circuit is completed over conductors 1 and 2 and the 20 subscriber's loop for the upper and lower windings of the line relay 5. Relay 5 upon operating, at its armature 6 completes a circuit for relay 8 and at armature 7 prepares a bridge across the outgoing trunk line 25 which latter operation is however without effect at this point. Relay 8 energizes and at armature 9 connects earth to release trunk conductor 3 so as to maintain the line switch operated and at armature 10 prepares the 30 impulsing circuit. The switch is now in condition to respond to the first digit dialled by the subscriber. When this operation takes place, a number of interruptions will be produced in the circuit of line relay 5 35 and it will deenergize a corresponding number of times; upon each deenergization a circuit is completed from earth, armature 6 and its back contact, armature 10 and its front contact, armature 15 and its back contact, 40 vertical magnet 16 to battery. A branch of this circuit also extends through the winding of relay 11, which thereupon energizes and being slow to release remains energized throughout the train of impulses. By the 45 operation of vertical magnet 16, the switch shaft and wipers are raised a number of steps corresponding to the digit dialled. The operation of relay 11 completes a circuit at armature 13 for the upper winding 50 of relay 17, and at armature 14 completes a low resistance bridge across the trunk conductors which latter operation is, however, without effect at this point. Relay 17 upon operating, at its armatures 18 and 19 completes a locking circuit for itself, which extends as follows:—battery, resistance, normally closed springs controlled by armature 28, armature 18 and its front contact, lower winding of relay 17, front contact and armature 19, front contact and armature 7, normally closed springs controlled by armature 31 to earth. This locking circuit becomes effective when the sending of impulses ceases, and thus relay 17 which is held up 60 over its upper winding during the transmis-

sion of impulses is then held locked over its lower winding. Relay 11 also at armature 12 completes a circuit for stepping relay 21 which becomes effective when the off normal contacts 26 close on the first vertical step 70 of the switch. This circuit extends as follows: earth, front contact and armature 9, armature 12 and its front contact, armature 29 and its back contact, interrupter contact 25, off normal contacts 26, 75 winding of relay 21 to battery. Relay 21 therefore operates, at armature 22 completes a locking circuit for itself, and at armature 23 prepares a circuit for the rotary magnet 24. Upon the deenergization of relay 11, 80 a circuit is completed at armature 12 and its back contact for rotary magnet 24 whereupon the switch wipers are rotated into engagement with the first set of bank contacts. The rotary magnet 24 by opening its 85 interrupter contact 25 breaks the locking circuit of relay 21 so that this deenergizes and opens the circuit of the rotary magnet at armature 23. If the test wiper 41 now finds earth on the contact with which it is in 90 engagement, a circuit is again completed for stepping relay 21 and on the operation of armature 23 the switch takes a further step. This cycle continues until test wiper 41 reaches a contact which is not earthed, for 95 instance, the contact 44, whereupon switching relay 27 is no longer short circuited, and energizes in series with stepping relay 21, which is however not operated at this time. Relay 27 at armature 29 connects 100 test wiper 41 through to release trunk conductor 3 and opens the initial energizing circuit of relay 21, at armature 30 prepares the circuit for the supervisory relays 32 and 36, at armature 15 opens the circuit of the 105 vertical magnet and at armatures 28 and 31 disconnects the lower winding of relay 17 from the local battery and earth connections and connects it over the trunk conductors 51 and 52 and back contact and armature 78 110 to the line relay 53 of the incoming selector shown in Fig. 2. As the armatures 28 and 31 control make-before-break springs, there is no discontinuity when they operate and relay 17 is thus maintained energized. Relay 53 now energizes and completes a circuit for relay 56 thus preparing the switch for operation in the usual manner. It will be noted that since the trunk line extending to the distant exchange comprises only two 115 conductors, there is no conductor leading away from contact 44, but this contact is multiplied to corresponding contacts in the banks of other selectors having access to this trunk line so as to prevent it being taken 120 into use by any of such other selectors. The operation of the incoming selector shown in Fig. 2 is substantially similar to that of the local selector, but as one or two important differences arise, this operation 125 130

will be traced through in detail. When the subscriber dials the second digit in the wanted number, the line relay 5 is momentarily deenergized a number of times and thereby operates its armatures 6 and 7. At armature 6 the usual circuit is completed for the series relay 11 and this operates to maintain relay 17 energized at its armature 13 and at armature 14 to connect the trunk conductors together so as to improve the impulsing circuit. The vertical magnet 16 cannot now be operated since armature 15 has left its back contact and relay 27 cannot be again short circuited owing to the operation of armature 29. The circuit for repeating impulses to the incoming selector extends as follows: earth, lower winding of relay 53, trunk conductor 52, contact 43, wiper 40, armature 31 and its front contact, armature 20 7 and its front contact, armature 14 and its front contact, front contact and armature 28, wiper 39, contact 42, trunk conductor 51, back contact and armature 78, upper winding of relay 53 to battery. A similar number 25 of interruptions is thus produced in the circuit of the line relay 53 of the incoming selector, and this therefore at armature 54 completes a circuit over armature 58 and its front contact for series relay 59 and in parallel 30 over armature 63 and its back contact to the vertical magnet 64. Series relay 59 acts in a similar manner to the series relay 11 of the first selector, and at armature 60 prepares a circuit for stepping relay 70, at armature 35 61 completes a circuit for the upper winding of relay 65 and at armature 62 connects the outgoing trunk conductors together. Relay 65 upon operating at armatures 67 and 68 locks itself up to local battery and 40 earth connections over the normally closed springs controlled by armatures 77 and 81 of switching relay 76 and at armature 66 shunts armature 78 for a purpose which will be appreciated shortly. The incoming selector 45 is thus stepped up to the desired level by the operation of the vertical magnet 64 and when off normal contact 75 closes on the first step, a circuit is completed for stepping relay 70 which at armature 71 completes a locking circuit for itself, and at armature 72 prepares a circuit for the rotary magnet 73. Consequently when relay 59 deenergizes 50 on the termination of the series of impulses, armature 60 engages its back contact and the hunting operation of the switch is initiated 55 and continues under the control of interrupter contact 74 in the manner described in connection with the first selector. When wiper 94 engages a contact which is not 60 earthed, for instance contact 97, switching relay 76 is energized in series with stepping relay 70 and at its armature 77 and 81 transfers the locking circuit through the lower winding of relay 65 to the line relay 104 of 65 the intermediate selector shown in Fig. 3.

Relay 76 moreover at its armature 63 opens the circuit of the vertical magnet to prevent this being further operated, at armature 80 prepares a circuit for the supervisory relays 70 and 88, at armature 79 places earth from armature 57 on test wiper 94, and at armature 78 opens a point in the circuit of line relay 53. Since however this armature has been shunted by armature 66 of relay 65, which is still operated, relay 53 remains operated 75 and consequently relay 17 of the local selector.

The intermediate selector shown in Fig. 3 is substantially the same as the standard selector and only differs therefrom in one or two minor details, the most important of which is the provision of make-before-break springs on the switching relay in the line circuit. When the switch is taken into use, line relay 104 operates and at its armature 105 completes a circuit for relay 106 which also operates and at armature 107 prepares the impulsing circuit. When the third digit is dialled by the calling subscriber, line relay 5 of the local selector is operated in the usual manner, thereby energizing series relay 11, which at armature 14 completes a low resistance circuit for repeating impulses by means of armature 7 at the same time maintaining relay 17 energized over its upper winding while its lower winding is short circuited. Relay 53 therefore operates similarly to relay 5, relay 59 completes an improved impulsing circuit at armature 62 and 90 impulses are thus repeated at armature 55 to the intermediate selector in Figure 3. Relay 65 is maintained energized over its upper winding during the transmission of impulses in a similar manner to relay 17. Upon the intermittent de-energization of line relay 104 a circuit is completed from earth, armature 120 and its back contact, armature 105 and its back contact, armature 107 and its front contact, winding of series 95 relay 108, winding of vertical magnet 109 to battery. The switch is thus stepped up in accordance with the digit dialled and relay 108 is energized throughout the series of impulses, and at armature 110 prepares the circuit of the rotary magnet. Stepping relay 111 is energized in the usual manner upon the first step of the switch and at armature 112 completes a locking circuit for itself and at armature 113 prepares a circuit for the rotary magnet 114. The hunting motion of the switch takes place substantially in the manner previously described and when a free trunk is found, for instance, that associated with contacts 125, 126 and 127, switching relay 117 is operated with the usual results, among them the disconnection of line relay 104 and of the transference of the circuit through the lower winding of relay 65 to line relay 154 of the connector shown in Fig. 120 115 125 130 4. Relay 154 thereupon energizes and at armature 155.

mature 155 completes a circuit for relay 156 which at its armature 157 prepares the impulsing circuit.

- When the subscriber dials the succeeding digit, the impulses produced are repeated by the local and incoming selectors in the manner previously described, and since there is a straight through connection by way of the intermediate selector, the relay 154 is operated similarly. Upon the first deenergization of relay 154, a circuit is completed from earth, armature 177 and its back contact, armature 155 and its back contact, armature 157 and its front contact, spring 162 and spring 160 with which it is normally in engagement, winding of relay 158, winding of vertical magnet 163 to battery. Relay 158 is operated as usual and remains operated throughout the train of impulses and at its armature 159 and its front contact serves to maintain its own circuit and that of the vertical magnet intact when off normal spring 162 engages spring 161 instead of spring 160 as occurs upon the first step of the switch. Relay 158 de-energizes when the sending of impulses ceases, and consequently the operating circuit responsive to the next and last series of impulses extends to the rotary magnet as follows: earth, armature 177 and its back contact, armature 155 and its back contact, armature 157 and its front contact, off normal springs 162 and 161, armature 159 and its back contact, back contact and armature 173, armature 179 and its back contact, winding of rotary magnet 169 to battery. Relay 164 is operated in parallel with rotary magnet 169 and remains operated throughout the train of impulses. At its armature 167 it prepares a circuit for the busy relay 170, at armature 166 disconnects the busy tone, at armature 165 shunts armature 171, and at armature 168 shunts armature 173. In case test wiper 184 passes over busy lines during the rotary movement, relay 170 will be operated, and at armature 172 will prepare a locking circuit for itself, while the operation of armatures 171 and 173 will be ineffective since they are shunted as explained above.
- Suppose in the first instance that the wanted subscriber is free when he is called; consequently when relay 164 deenergizes, busy relay 170, if previously operated, will be deenergized, and a circuit will be completed as follows: earth on release trunk conductor 152 (which is provided at armature 57 of the incoming selector), armature 172 and its back contact, upper winding of relay 174, back contact and armature 167, wiper 184, contact 187, winding of switching relay of the called subscriber's line switch, winding of stepping magnet of the line switch to battery. Relay 174 and the switching relay are energized in series in this circuit, but not the magnet, and the

switching relay in well known manner partially operates its armatures to clear the called line of its normal battery and earth connections. Relay 174 upon operating, at armature 178 completes a locking circuit for itself to release trunk conductor 152, at armature 179 opens the circuit of the rotary magnet, at armature 177 disconnects earth from armature 155 and connects direct earth to test contact 187, at armatures 176 and 180 opens the circuit of the line relay 154 and at armatures 175 and 181 completes the ringing circuit from the ringing generator RG through the upper winding of the ringing trip relay 189. Ringing current from the generator and earth are now applied alternately to the lower trunk conductor so that the subscriber's bell is rung intermittently in the usual manner.

When the wiper relay 174 operates, the circuit of the line relay 154 is broken and consequently also the circuit of the relay 65 in the incoming selector, Fig. 2. This therefore releases its armatures, at armature 67 connects up the supervisory relays 82 and 88 to the upper trunk conductor extending to the connector and at armature 68 connects up a retard coil 69 to supply talking battery to the wanted party. Relay 65 also at armature 66 opens the circuit through the upper winding of relay 53 and hence also the circuit of the relay 17 in the local selector. Relay 17 on releasing, at armature 18 connects up the supervisory relays 32 and 36 and at armature 19 connects up the retard coil 20 to supply current for maintaining the line relay 53 energized over its lower winding. The circuits are now in what may be described a waiting condition, all apparatus used only during the setting up of the connection has been disconnected and the necessary circuits for supervision have been prepared.

When the called party replies the ringing trip relay 189 is energized in the usual manner and at its armature 191 completes a locking circuit for itself to release trunk conductor 152 and at armatures 190 and 192 disconnects the ringing current and connects the speaking leads through.

Upon the operation of relay 189 a circuit is completed as follows: battery, retard coil 69, back contact and armature 68, front contact and armature 55, front contact and armature 81, wiper 93, contact 96, lead 102, front contact and armature 121, wiper 123, contact 126, lead 153, front contact and armature 192, armature 181 and its front contact, wiper 183, contact 186, subscriber's loop, contact 185, wiper 182, front contact and armature 175, armature 190 and its front contact, lead 151, contact 125, wiper 122, armature 118 and its front contact, lead 101, contact 95, wiper 92, armature 77 and its front contact, armature 67 and its back

- contact, armature 80 and its front contact, lower winding of relay 82, winding of relay 88 to earth. Relays 82 and 88 both operate in this circuit, and relay 82 at armature 88 completes a locking circuit for itself by way of its upper winding, at armature 84 short circuits the high resistance 85, and at armature 87 opens a point in the circuit for maintaining relay 56 operated.
- 5 **10** Relay 88 upon operating, at armature 91 closes a point in the circuit just mentioned for relay 56, at armature 80 short circuits the lower winding of relay 82, so as to secure a better balanced speaking circuit, and at armature 89 connects battery through the retard coil 86 to conductor 51. A circuit is now completed as follows: battery, retard coil 86, armature 84 and its front contact, front contact and armature 89, lead 51, contact 42, wiper 39, armature 28 and its front contact, armature 18 and its back contact, armature 30 and its front contact, lower winding of relay 32, winding of relay 36 to earth. Both relays 32 and 36 operate in this circuit, and the former at armature 33 completes the locking circuit for itself by way of its upper winding, at armature 34 opens a point in the circuit for maintaining relay 8 energized and at armature 35 completes a circuit for operating the calling subscriber's meter. Relay 36 at armature 37 short circuits the lower winding of relay 32 so as to balance the speaking circuit and at armature 38 closes a point in the circuit previously mentioned for maintaining relay 8 energized. The connection has now been completely established and since it is successful the calling subscriber's meter has been operated to charge him accordingly. Feeding current is supplied to the calling party from the windings of relay 5 of the first selector and to the called party from the retard 69 and relay 88 in the incoming selector.
- 45 The connection is released under the control of the calling party. When he replaces his receiver, a prolonged de-energization of relay 5 is effected and it therefore opens the circuit of relay 8. This de-energizes after a short interval and removes earth from release trunk conductor 3 thereby releasing the line switch and relay 27 and removing earth from contact 44 so that the trunk line is again accessible to other selectors. When both relays 5 and 8 have deenergized a circuit for the release magnet 46 is completed and the switch is restored to normal, this circuit being opened by off normal contacts 45 when the switch has returned to its normal position. The release of relay 5 also at armature 7 opens the circuit for maintaining relay 53 energized, so that this deenergizes and shortly afterwards relay 56 also. Thereupon at armature 57 earth is removed from the release trunk conductor, whereupon re-
- lays 76 in the incoming selector 117 in the intermediate selector 189 and 174 in the connector are de-energized, and these switches are restored to normal in the usual manner.
- 70 The case will now be considered in which the wanted party is busy when he is called. In this case when the wipers of the connectors come to rest, test wiper 184 will find earth on contact 187 with which it is in engagement, and consequently relay 170 will be energized. Accordingly when relay 164 deenergizes, relay 170 is locked up to the release trunk conductor over its armature 172 and the normally closed springs controlled by armature 167 and at its armature 171 it operates to disconnect the upper winding of line relay 154 and to connect busy tone and busy flash battery through a high resistance to the line alternately. When battery is first removed from the upper trunk conductor relay 65 is deenergized and the apparatus is operated to the waiting condition. When battery is again connected up, the following circuit is completed; busy flash battery, high resistance 193, back contact and armature 166, front contact and armature 171, armature 176 and its back contact, lead 151, contact 125, wiper 122, armature 118 and its front contact, lead 101, contact 95, wiper 92, armature 77 and its front contact, armature 67 and its back contact, armature 80 and its front contact, lower winding of relay 82, winding of relay 88 to earth. Owing to the inclusion of the high resistance 193 in this circuit, only relay 88 operates, thereupon at its armature 91 completing an auxiliary circuit for relay 56 at armature 90 short circuiting the lower winding of relay 82, and at armature 89 completing the following circuit: battery, retard coil 86, high resistance 85, front contact and armature 89, lead 51, contact 42, wiper 39, armature 28 and its front contact, armature 18 and its back contact, armature 30 and its front contact, lower winding of relay 32, winding of relay 36 to earth. Owing to the inclusion of the resistance 85 in this circuit, only relay 36 operates and short circuits the lower winding of relay 32 and holds relay 8 energized. As however relays 36 and 88 are energized at intervals, relays 8 and 56 fall away when these relays are deenergized after the calling subscriber hangs up. The calling subscriber will hear the busy tone and will accordingly realize that he cannot obtain his connection and will hang up his receiver. When he does so the connection is released in the manner previously described. It will be noted that in this case which is an unsuccessful connection, since the relay 32 is not operated, no metering takes place. The operation in case a selector is driven to the 11th contact owing to all of a group of trunks being busy is substantially the same, busy tone and busy flash bat-
- 75 80 85 90 95 100 105 110 115 120 125 130

ter through a high resistance being connected up alternately to the upper trunk conductor. The relays 65 and 17 are released previous to this due to the wipers being disconnected and the battery connections for maintaining the relays energized being thus removed.

Considering now the case in which a connection is extended from an automatic subscriber to an operator for information or inquiry, suppose that the circuits of the operator's position shown in Fig. 5 are arranged to fit on after Fig. 3 in place of Fig. 4 and suppose further that a connection has been extended over the switches shown in Figs. 1 and 2 and 3 in the manner described above. When the intermediate selector in Fig. 3 switches through, a circuit is completed as follows: battery, retard coil 207, armature 210 and its back contact, lead 202, contact 126, wiper 123, armature 121 and its front contact, lead 102, contact 96, wiper 93, armature 81 and its front contact, armature 55 and its front contact, armature 68 and its front contact, lower winding of relay 65, front contact and armature 67, front contact and armature 77, wiper 92, contact 95, lead 101, front contact and armature 118, wiper 122, contact 125, lead 201, back contact and armature 216, normally closed springs controlled by armature 205, winding of relay 204 to earth. Relay 204 operates in this circuit and at armature 206 lights the calling lamp 215, and at armature 205 completes a locking circuit for itself dependent upon armature 209. The opening of the initial energizing circuit for relay 204 opens the circuit of relay 65 in the incoming selector which therefore deenergizes and prepares the supervisory circuits in the manner previously described. Upon noting the lighted condition of the lamp 215, the operator will plug into the jack whereupon the sleeve relay 208 is operated. This then at its armature 212 extinguishes the lamp 215, at armature 211 connects impedance 214 across the jack springs, at armature 210 disconnects retard 207 from the lower trunk lead 202 and connects it through the high resistance 213 to the upper trunk lead 201, at armature 216 opens the initial energizing circuit of relay 204 and at armature 209 opens the original locking circuit of relay 204 and connects it to the lower trunk lead 202 so that it is now maintained energized by battery through the retard coil 69. The effect of the operation of relay 208 is to complete a circuit as follows: battery, retard 207, armature 210 and its front contact, resistance 213, trunk conductor 201 through the intermediate selector to armature 67 and its back contact in the incoming selector, thence by way of armature 80 and its front contact, lower winding of relay 82, winding of relay 88 to earth. Owing to the inclusion

of the resistance 213 in this circuit only relay 88 operates, and at its armature 91 completes a holding circuit for relay 56 thereby placing the release of the connection under the control of the operator, at armature 90 short circuits the lower winding of relay 82 and at armature 89 completes a circuit including the high resistance 85 through relays 32 and 36 of the first selector. As previously mentioned, relay 32 cannot operate in series with this resistance, but relay 36 operates and at its armature 38 completes a holding circuit for relay 8. In this case also since relay 32 is not operated, no metering takes place. When the calling party has obtained the required information and hangs up his receiver, line relay 5 is deenergized whereupon it releases its armature 7, thus opening the circuit of line relay 53 in the incoming selector. This in similar manner releases its armature 58 thereby opening the circuit of relay 204 at the operator's position. This then releases and completes a circuit over armature 206 and its back contact, front contact and armature 212 for the supervisory lamp 215. When this occurs the operator is notified that the calling subscriber has hung up, and she accordingly removes the plug thereby deenergizing relay 208. In consequence battery through retard coil 207 is removed from the upper trunk conductor and relay 88 in the incoming selector, Fig. 2, deenergizes. Upon the opening of contact 91 which then takes place, relay 56 is no longer held up, and by releasing its armature 57 removes earth from the release trunk conductor so that this switch and the intermediate selector are released in the usual manner. The release of armature 89 of relay 88 also opens the circuit of relay 36 of the first selector; in consequence of which relay 8 is deenergized, earth is removed from release trunk conductor 3 and the first selector and subscriber's line switch are restored to normal. Consider now the case in which a connection is set up by an operator to an automatic subscriber in a distant exchange. In order to obtain a complete circuit for this connection, Figs. 6 and 7 should be substituted for Figs. 1 and 2, so that the connection will thus extend through Figs. 6, 7, 3 and 4. When the calling subscriber removes his receiver, the A operator is notified in the usual manner by the lighting of the calling lamp and inserts the answering plug P' into his jack J' and after throwing the key K to the left or answering position ascertains his requirements. She then inserts the calling plug P² in the jack J² associated with a free trunk line leading to the desired exchange, the trunk being recognized as free if the lamp 306 is not lighted. When the plug is inserted, a circuit is closed for lamp 310 and relay 304 in series over the sleeve of

the plug; the lamp 306 is thus lighted by the operation of armature 305. The operator then throws the key K to the right or dialling position whereupon a circuit is completed for the line relay of the operator's incoming selector as follows: battery, shunt springs 302 of the dial, impulse springs 303, upper contact of the spring 300 of the key K, tip of plug P², tip spring of jack J², 5 upper trunk conductor 251, back contact and armature 279, normally closed springs controlled by armature 265, winding of relay 253 to earth. It should be noted that a preliminary impulse due to the operator inserting the plug into the jack is prevented 10 since the tip of the plug is connected to earth via relay 307 while the conductor 252 is disconnected and the conductor 251 is also connected to the earthed relay 253. When, 15 however, the dialling key is thrown relay 253 operates in the circuit just described and at its armature 254 completes a circuit for release relay 256 and at armature 255 prepares a circuit across the conductors 295 20 and 296 outgoing to the next switch. Relay 256 upon operating, at armature 257 connects earth to the release trunk conductor, at armature 258 prepares the impulsing circuit, and at armature 259 completes a circuit 25 by way of back contact and armature 282 for the lower winding of relay 264 which relay then operates. At armature 265 it connects line relay 253 to the upper trunk conductor independently of armature 279, at 30 armature 266 and 267 completes a locking circuit for itself through its upper winding and at armature 268 connects battery to the lower trunk lead 252 so as to maintain the 35 circuit of line relay 253 when the shunt springs open upon the dial being moved from its normal position preparatory to the transmission of impulses.

The operator will now dial the first digit in the wanted number, whereupon a number 40 of interruptions will be produced in the circuit of line relay 253 and it will deenergize a corresponding number of times. Upon each deenergization a circuit is completed as follows: earth, armature 254 and its back contact, armature 258 and its front contact, armature 269 and its back contact, winding of vertical magnet 270 to battery; the switch wipers are therefore raised a number of steps corresponding to the level desired. A 45 branch of this circuit extends through relay 260 which operates and remains energized throughout the train of impulses since it is slow to release. Relay 260 at armature 263 completes an alternative circuit for relay 264, although this is unnecessary at this point since the circuit by way of armatures 259 and 282 is still closed, and at armature 261 closes a low resistance bridge across the outgoing 50 trunk conductors although this also is without effect at the present time, since armatures

278 and 283 have not yet been operated. Relay 260 also at armature 262 prepares a circuit for the stepping relay 271 which is completed as follows when off normal springs 276 close: battery, winding of relay 271, off normal springs 276, interrupter contact 275, back contact and armature 281, armature 262 and its front contact, armature 257 and its front contact, earth. Relay 271 55 operates in the usual manner to prepare a circuit at armature 272 for the rotary magnet 274 and at armature 273 to complete a locking circuit for itself. When relay 260 deenergizes at the end of the train of impulses, the circuit of rotary magnet 274 is completed by way of the normally closed springs controlled by armature 262 and the switch takes one step, whereupon stepping relay 271 is deenergized by the opening of the interrupter contact 275. In case test wiper 297 finds earth on the contact with which it is now in engagement relay 271 will be again energized and the switch will take a further step. This operation continues until a free trunk line is found whereupon switching relay 277 is no longer short circuited 60 and operates, thereby at its armatures 278 and 283 connected the upper winding of relay 264 through to the line relay 104 of the intermediate selector. Relay 277 also at 65 armature 279 prepares another circuit for line relay 253; at armature 280 prepares circuits for the supervisory relay 284 at armature 269 opens a point in the circuit of the vertical magnet and at armature 282 70 opens the initial energizing circuit for relay 264.

When the next digit is dialled a number 75 of interruptions are produced in the circuit of line relay 253 in the usual manner and it deenergizes accordingly and by means of its contact 255 repeats the impulses to the succeeding selector, in this case the intermediate selector shown in Fig. 3. Relay 260 80 is energized throughout the series of impulses and at its armature 261 connects the outgoing trunk conductors together so as to improve the impulsing and at its armature 263 completes a circuit through the lower winding of relay 264 so that this relay 85 is not deenergized when its upper winding is short-circuited by the operation of armature 261. The impulses cannot now operate the vertical magnet 270 since the armature 269 has been operated, nor can the 90 operation of armature 262 again energize stepping relay 271 since armature 281 has been operated.

The connection is extended through the 95 intermediate selector in the manner previously described and the remaining two series of impulses operate the connector shown in Fig. 4 in the usual manner, being repeated by the operator's selector repeater in the 100 same way as was the previous train.

Assuming that the wanted party is free when his line is tested, the circuit through the upper winding of relay 264 is broken upon the operation of the wiper relay 174 and relay 264 deenergizes. Thereupon line relay 253 is connected over the normally closed springs controlled by armature 265 and armature 279 and its front contact to the lower trunk conductor 252 and hence as long as the key K is operated to battery over the shunt springs 302 and after the key is released to battery through the retard 308. Relay 264 also at armatures 266 and 267 prepares the feeding bridge for the wanted party's transmitter, this circuit including the supervisory relay 284 and retard 287. When the called party replies this circuit is completed upon the operation of the ringing trip relay 189 and relay 284 is then energized. Thereupon at its armature 285 it connects the retard coil 286 to conductor 251 and hence completes a circuit over the tip spring of jack J², tip of plug P², spring 300 of the key K and its normal contact, upper right-hand winding of the repeating coil to earth through the winding of the supervisory relay 307. Relay 307 therefore operates its armature 309 thereby extinguishing the lamp 310 and giving the calling operator answering supervision.

The connection has now been completely established and the two subscribers may converse, talking battery being supplied to the calling party from the cord circuit and to the called party from the incoming selector. When they have finished their conversation they will both replace their receivers. When the calling subscriber hangs up, the usual clearing supervision is given to the A operator by the lighting of lamp 311. When the called man hangs up, the circuit of relay 284 is broken and it deenergizes, thereby at armature 285 opening the circuit of the supervisory relay 304 which deenergizes and lights the supervisory lamp 310. The operator upon noting the lighting of both lamps 310 and 311 removes both plugs P' and P² whereupon the circuit of line relay 253 is opened and all the apparatus is restored to normal in the usual manner.

In case the called man is found busy, busy flash battery and busy tone will be connected up alternately in the connector in the manner described, after the supervisory condition has been produced by the energization of the busy relay 170. In response to every connection of busy flash battery, relay 284 in the operator's selector will be operated and by attracting its armature 285 will complete a circuit for the supervisory relay 307; the lamp 310 will thus be caused to flash. The A operator upon noting the flashing of the supervisory lamp will inform the calling party accordingly and take down the connection whereupon all the apparatus will

be restored as previously described. It will be noted that in the case of the operator's selector only one supervisory relay 284 is provided since the A operator initiates the metering operation and it is unnecessary for the connection to be placed under the control of the called operator in case a call should be extended for information or enquiry.

It will be noted that although during supervision after effective dialling operations have been completed, certain relays and retard coils are connected up to earth and battery at both ends of a trunk line, yet during dialling all impulsing circuits over trunk lines are similar to those present in standard two wire dialling circuits with battery feed at one end (the incoming end) only and impulses transmitted by opening a loop circuit including the two talking conductors of a trunk in series.

Further it will be noted that the impulsing circuits are prepared before the transmission of impulses has commenced and the supervisory circuits are prepared immediately after all effective dialling operations have ceased even if some dialling operations which are not effective due to a group of lines being busy should still be proceeding.

Having now particularly described and ascertained the nature of our said invention and in what manner the same is to be performed, we declare that what we claim is:

1. In an automatic telephone system in which the impulses for setting the automatic switches are sent by opening and closing a circuit including the two talking conductors in series, means for subsequently controlling supervision over each of the talking conductors independent of the other.

2. In an automatic telephone system in which control is exercised by the calling subscriber over the talking conductors in series until all the setting operations have been performed, means for effecting circuit changes such that all subsequent control over the maintenance of the connection by the calling subscriber is exercised over one talking conductor independent of the other.

3. In a combined manual and automatic telephone system, in which an impulse sender is associated with an operator's position to enable the operator to effect the setting of the automatic switches, means including a switching device in one automatic switch for reversing the battery connections to the talking conductors after the automatic switches have been operated so as to place the circuits in condition for the transmission of supervisory signals, each of said signals being transmitted over one talking conductor independent of the other.

4. In a combined manual and automatic telephone system in which an impulse sender is associated with an operator's position to

enable the operator to effect the setting of the automatic switches, a normally-open switch-control circuit extending to the first of said switches including the two talking conductors and said sender in series, means for preparing said switch control circuit by connecting said sender thereto, and means responsive to such operation and controlled over one talking conductor independent of 10 the other for completing said switch-control circuit.

5. In a combined manual and automatic telephone system in which an impulse sender is associated with an operator's position to enable the operator to effect the setting of the automatic switches, a normally-open switch-control circuit extending from the operator's position to the first automatic switch including the two talking conductors and 15 said sender in series, a preparing circuit including one talking conductor independent of the other, means in the first automatic switch controlled over said preparing circuit for completing the said switch-control 20 circuit before the sender is turned off normal, and means responsive to the turning of said impulse sender off normal for opening said preparing circuit.

6. In a telephone system, a trunk line extending to an automatic impulse repeater, a train of automatic switches operated by said impulse repeater to set up a telephone connection, a repeating relay in said repeater controlled over the two conductors of said 35 trunk line in series during the repeating of impulses, means for setting up supervisory conditions in the established connection, and means for maintaining said repeating relay energized thereafter over one talking conductor of said trunk line independent of the other.

7. In a telephone system, a trunk line extending to an automatic impulse repeater, a train of automatic switches controlled by 45 said repeater to set up a telephone connection, a supervisory relay in said repeater, and means revertively controlled over the established connection responsive to its completion for initially connecting said supervisory relay to only one of the talking conductors outgoing from said repeater.

8. In a telephone system, an automatic impulse repeater, a trunk line outgoing from said repeater including two talking conductors, a bridge across said talking conductors free from local battery and ground connections, a train of automatic switches, means for operating said train of automatic switches to set up a telephone connection by 55 interrupting the said bridge, means effective subsequent to the establishment of said connection for opening said bridge, for establishing a battery connection to one of said talking conductors, and for establishing a ground connection to the other talking con-

ductor, and supervisory apparatus controlled through said ground connection and independent of said battery connection.

9. In a telephone system as claimed in claim 8, in which the switching device for 70 replacing the bridge with the battery and ground connections includes a relay energized in said bridge by current supplied over the outgoing talking conductors during the setting up of the connection, means in the 75 switch train for deenergizing the said relay responsive to the establishment of the connection by stopping the current flow over the outgoing conductors.

10. In an automatic telephone system in 80 which current for the purpose of setting the switches is fed back over the two talking conductors in series during the process of setting up the connection, means for suitably altering the circuits so that current for speaking and holding purposes is fed forward over the same conductors thereafter, 85 said altering means comprising contacts on a slow acting relay energized during the setting operation by the current which is fed back.

11. In an automatic telephone system in 90 which the automatic switches are set by impulses transmitted over a talking conductor and in which a switch-over operation is performed to switch the circuits from setting conditions to talking and supervisory conditions responsive to the completion of the connection, a switch-over relay for performing the said switch-over operation, means 95 for energizing said switch-over relay in a local circuit responsive to the transmission of the first series of setting impulses, and means for maintaining said relay energized alternately in a local circuit and in the 100 setting circuit until the connection has been set up, and means for then opening the setting circuit to deenergize said switch-over relay.

12. In a telephone system, means including a trunk line and an automatic switch for setting up a connection from a calling line to a called line of one class and for setting up a connection from the same calling line to the called line of another class, two 115 battery feed relays connected in series between one of the talking conductors of said trunk line and the exchange battery, means for operating both of said relays over the first connection, and means for operating one 120 of said relays over the second connection and for preventing the operation of the other.

13. In an automatic telephone system in 125 which setting and supervision are effected over the talking conductors under different circuit conditions, means for switching over from setting conditions to supervisory conditions responsive to the completion of the connection in one case and for performing 130

- an identical switch-over operation responsive to the encountering of a busy trunk group in another case, and means whereby supervision from the calling party is transmitted forward over the connection in the direction of the called party over one talking conductor independent of the other and whereby supervision from the called party is transmitted back in the direction of the calling party over the said other conductor independent of said one conductor.
14. In an automatic telephone system in which the setting up of a connection through successive switching stages and supervision are effected over the talking conductors under different circuit conditions, means for switching over from setting conditions to supervisory conditions responsive to a busy condition encountered at any one of a plurality of switching stages, and means whereby supervision from the calling party is transmitted forward over the connection in the direction of the called party over one talking conductor independent of the other

and whereby supervision from the called party is transmitted back in the direction of the calling party over the said other conductor independent of said one conductor.

15. In a telephone system as claimed in claim 12, a holding circuit controlled jointly by said relays for maintaining a connection established.

16. In a telephone system as claimed in claim 12, a register for registering completed connections of one class, and a circuit for controlling said register controlled jointly by said relays.
